I. SHULMAN

HOLDING FRAME FOR DRAWINGS AND THE LIKE

Filed Oct. 29, 1927.

FIG. 1.

FIG. 3.

FIG. 2.

FIG. 4.

INVENTOR

Isidor Shulman

BY

Maurice Block

ATTORNEY

UNITED STATES PATENT OFFICE.

ISIDOR SHULMAN, OF BROOKLYN, NEW YORK.

HOLDING FRAME FOR DRAWINGS AND THE LIKE.

Application filed October 29, 1927. Serial No. 229,785.

This invention relates to improvements in holding frames for drawings and the like, and has for one of its objects the provision of means for clampingly holding a drawing 5 and a superimposed sheet of tracing cloth thereon and to prevent any relative movement between the said drawing and tracing cloth.

Another object of the invention is to provide a structure of this nature, the supporting base of which may be made to assume an inclined position to the horizontal plane when a drawing and a superimposed sheet of tracing cloth is clamped thereon.

15 A further object of the invention is to provide a device of this nature, which is simple and inexpensive, and yet efficient and substantial in construction.

Other objects and advantages will appear 20 as the nature of the improvements is better understood, the invention consisting substantially in the novel arrangement and correlation of instrumentalities herein fully described and illustrated in the accompanying drawings, wherein similar reference characters are used to describe corresponding parts throughout the several views, and then finally pointed out and specifically defined and indicated in the appended claims.

25 The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purposes of illustration, is shown in the accompanying drawings, in which

30 Figure 1 is a perspective view of my improved holding frame shown in closed or clamping position.

Figure 2 is a sectional view taken on line 2-2 Fig. 1.

35 Figure 3 is a similar view to that shown in Fig. 2, but with the parts shown in open position and Fig. 4 is a fragmental top plan view of the supporting base or table.

Referring now to the drawing in detail 5 indicates a frame hingedly mounted on a base or table 6. The said base or table 6 is 40 preferably made of a single sheet of metal

and the rear edge thereof is rolled over and extends laterally beyond the body, to form hinge pins 7-7 which are inserted into corresponding openings in the rear upper portion of the frame 5, the said frame 5 being 45 slightly sprung outwardly to permit of the above insertion. The body portion of the table 6 is provided with depressions forming strengthening or stiffening ribs 8-8 which run substantially the entire length of 50 the said table body. The said table is further provided at the front thereof with a depending wall 9 and a supporting section 10 terminating in a bead 11.

The frame 5 is provided with an opening 55 12 at the top wall 5^a thereof and has a rear wall 13 of a height greater than the front wall 14 in order that the said top wall inclines downwardly from the rear to the front to conform to the inclination of the table 6 60 and to overlie same. Side walls 15 and 16 depend from the top wall 5^a. The frame 5 is also preferably made of a single sheet of metal and is provided at the bottom of the rear, front, and side walls thereof, with 65 beads 17 through which passes a rectangular wire frame 18 to give rigidity to the frame. The bead 17 on the front wall 14 in conjunction with the bead 11 on the table forms a locking means for locking in position a 70 drawing 20 or the like and a superimposed sheet of tracing cloth 21 between the table top and the frame 5. The said drawing and sheet of tracing cloth are maintained in lateral and longitudinal alinement by the 75 walls of the frame 5.

The operation of the device is as follows:

If it is desired to insert a drawing and a sheet of tracing cloth into the holder, the frame 5 is swung upwardly on its hinges 7-7 into the Fig. 3 position by holding the bead 11 down and pulling upwardly on a ring 23 provided for this purpose, the drawing and tracing cloth are placed on the table top 6 even with the edges thereof and the frame 5 is then swung downwardly until the front bead 17 comes into locking engagement with the bead 11 on the base portion 10. The parts are then in position to permit the user to trace the drawing or the 105 like without fear that the same or tracing cloth will move relatively to each other.

From the foregoing it will be seen that I have provided a simple and efficient holding frame for drawings, to securely hold therein 110

a drawing and a sheet of tracing cloth superimposed thereon and to readily remove the said drawing and tracing when desired.

Having described my invention, what I claim as new and desire to secure by Letters Patent is:—

1. In a drawing frame adapted to hold a plurality of sheets superimposed upon one another, a table, a hinge pin portion integral 10 with the table at one end thereof, a wall depending from the opposite end of the table and integral therewith, a base portion integral with and bent at an angle to the wall, a frame hingedly mounted on the table and 15 provided with an opening in the top wall thereof, depending front, rear and side walls

on the frame integral with the top wall, a bead on each of the depending walls, a reinforcing wire frame in the beads, and a bead on the table base coacting with the bead 20 on the front wall of the frame to form locking means between the table and frame.

2. In a holding device for drawings, a frame, a downwardly sloping top wall on the frame having an opening therein, and a 25 table beneath the top wall hingedly connected to the frame, said table being parallel to the top wall when in closed position and adapted to assume a horizontal position when the frame is swung upwardly.

ISIDOR SHULMAN.
